CLAIM

The ornamental design for an electric vehicle charging station, as shown and described.

DESCRIPTION

FIG. 1 is a front perspective view of a electric vehicle charging station showing my new design.

FIG. 2 is a front elevational view thereof.

FIG. 3 is a top plan view thereof.

FIG. 4 is a left side elevational view thereof; and,

FIG. 5 is a right side elevational view thereof.

The back and the bottom of the electric vehicle charging station are flat and unornamented.

The claimed electric vehicle charging station encloses a charging control box and holds a cord to connect to the vehicle. It may sit on the ground.
